TOOL FOR SPLICING AND TIGHTENING
BARBED WIRE

Gust D. Regas, Newell, S. Dak.

Application September 15, 1939, Serial No. 295,150

6 Claims. (Cl. 254—161)

This invention relates to wire tighteners and more particularly to a tool for splicing and tightening the barbed wires of fences and the like.

The object of the invention is to provide a tool of simple and inexpensive construction, by means of which the adjacent ends of a broken barbed wire may be securely connected and the slack in the wire taken up so as to keep the fence wires tight and uniformly spaced at all times.

10 A further object of the invention is to provide a tool of the class described comprising a bar having oppositely disposed wire-gripping members mounted thereon and provided with an intermediate loop-forming pin, said bar having operating handles extending laterally from one side thereof so that by gripping said handles and partially rotating the tool the pin will form a connecting knot or loop at the broken ends of the wire and a further rotation of the tool will take 20 up all sag or slack in said wire.

A still further object of the invention is generally to improve this class of devices so as to increase their utility, durability and efficiency.

In the accompanying drawings forming a part 25 of this specification and in which similar numerals of reference indicate corresponding parts in all the figures of the drawings:

Figure 1 is a side elevation of a combined wire splicing and tightening tool constructed in accordance with the present invention,

30 Figure 2 is a top plan view,

Figure 3 is a similar view showing the manner of forming a loop or knot in the broken ends of the barbed wire for connecting the same,

35 Figure 4 is a detail perspective view of one of the wire-gripping members, the parts thereof being shown separated and in position to be assembled on the body of the tool,

Figure 5 is a detail transverse sectional view 40 showing the manner of inserting the broken end of a barbed wire in one of the gripping members,

Figure 6 is a similar view showing the corrugated eccentric disk gripping the wire,

45 Figure 7 is a side elevation showing the tool in position on a barbed wire fence,

Figure 8 is a similar view showing the tool partially rotated, and

Figure 9 is a side elevation showing the position of the tool after connecting the broken ends 50 of the barbed wire and taking up the slack therein.

The improved barbed wire splicing and tightening tool forming the subject-matter of the present invention comprises a longitudinally disposed body portion 5, preferably in the form of a flat metal bar, to the opposite ends of which are

secured in any suitable manner upstanding operating handles 6. Depending from the lower surface of the bar 5 and preferably formed integral therewith is a tapered loop or knot-forming pin 7, the small end of which is preferably pointed, 5 as indicated at 8.

Disposed on opposite sides of the pin 7 are wire-gripping members 9, each consisting of a flat disk 10 mounted for rotation on a pin 11 extending through the body portion or bar 5 in 10 spaced relation to the adjacent handle 6. The periphery of the disk 10 is formed with a depending guard flange 12 having a portion thereof cut away to form a stop lug 13. Mounted for rotation on the pin 11 and bearing against the adjacent 15 face of the disk 10 is an eccentric 14, the edge of which is preferably corrugated or roughened, as indicated at 15, so as to prevent slipping of the barbed wire when taking up the slack therein.

Slidably mounted on the eccentric 14 is a latch 20 or keeper 16 having a slot 17 therein for the reception of the pin 11, and bearing against the keeper 16 is a washer 18, the adjacent end of the pin 11 being upset to form a head 19 which bears against said washer and serves to hold the several elements comprising the gripping member 25 in position on the bar 5. One end of the latch or keeper 16 is provided with a reduced neck 20 terminating in a transversely disposed finger-piece 21 to facilitate moving the keeper to operative and inoperative positions. The keeper 16 is so disposed that, when a forward longitudinal movement is imparted thereto, the free end of the keeper will fit over the cut-away portion on the flange 12 and bear against the stop lug 13 so 30 as to confine the adjacent end of the broken barbed wire between the flange 12 and the eccentric 14. When the keeper 16 is moved to retracted position, the wire will be exposed and the tool may be easily removed therefrom, as 35 will be readily understood.

In operation, the keepers 16 are moved to retracted position and the broken ends of the barbed wires inserted between the flanges 12 and eccentrics 14, as best shown in Figure 5 of 45 the drawings, after which the keepers 16 are moved forwardly until said keepers engage the stop lugs 13, thus preventing accidental displacement of the broken ends of the barbed wire during the splicing operation. The operating handles 6 are then grasped and the tool partially rotated which causes the broken ends of the barbed wire to coil around the pin 7 and thus form a connecting loop or knot 22 in said wires, as best shown in Figure 3 of the drawings. 50 55

A further rotation of the tool will cause the clamping members to exert a longitudinal pull on the barbed wires so as to take up any sag or slack therein. After the broken ends of the 5 barbed wires have been connected by the knot or loop 22 and the desired tension imparted to the fence wire, the tool may be readily removed from the barbed wire by moving the keepers 16 to retracted position and allowing the knot or 10 loop 22 to slip over the pointed end of the pin 7, as will be readily understood.

It will, of course, be understood that the tools 15 may be made in different sizes and shapes and constructed of any suitable material without departing from the spirit of the invention.

Having thus described the invention, what is claimed as new is:

1. A tool of the class described comprising a body portion having handles projecting from one 20 side thereof, a loop-forming device extending laterally from the other side of the body portion, and wire-gripping members mounted on the body portion at opposite sides of the loop-forming device.

2. A tool of the class described comprising a longitudinally disposed bar, operating handles projecting from one side of the bar, an intermediate loop-forming pin extending laterally from the other side of said bar, and wire-gripping 25 members mounted on the bar adjacent the handles.

3. A tool of the class described comprising a bar, a loop-forming pin projecting from one side of the bar, operating handles on said bar for rotating the tool, wire-gripping members pivotally mounted on the bar at opposite ends thereof and each comprising a disk having a lateral guard 30 flange, a portion of which is cut-away to form a stop lug, an eccentric disposed in contact with the disk, a keeper slidably mounted on the eccentric and movable into engagement with the

stop lug, and a pin mounted on the bar and extending through the disk, eccentric and keeper for holding the parts in assembled position.

4. A tool of the class described comprising a bar, a loop-forming pin extending laterally from one side of the bar intermediate its length, operating handles extending laterally from the opposite side of the bar, and wire-gripping members pivotally mounted on the bar at opposite sides of the loop-forming pin and each provided 10 with a sliding keeper for preventing displacement of a barbed wire when in position on the gripping member.

5. A tool of the class described comprising a bar, spaced wire-gripping members mounted on 15 one side of the bar and adapted to clamp the adjacent ends of a broken barbed wire, operating handles extending laterally from the other side of the bar, and a wire-engaging pin disposed between the wire-gripping members whereby 20 when the tool is rotated the pin will form a loop in the wire to connect the broken ends of said wire and simultaneously take up slack in the wire.

6. A tool of the class described comprising a 25 body portion, operating handles carried by the body portion, a wire loop-forming pin extending from one side of the body portion, and wire-gripping members mounted on the body portion at each side of the loop-forming pin, each wire-gripping member comprising a rotating disk having a guard flange terminating in a stop lug, an eccentric engaging the disk, a longitudinally slotted keeper, and a pin extending through the body portion and said disk, eccentric and keeper 30 respectively for rotatably holding the parts in position on the body portion, said keeper being provided with a reduced neck terminating in a lateral finger-piece for moving the keeper in and out of engagement with the stop lug 35
